UNITED STATES PATENT OFFICE.

CHARLES S. THOMPSON, OF PARK RIDGE, AND WILLIAM B. LONG, OF CHICAGO, ILLINOIS, ASSIGNORS TO UNION SPECIAL MACHINE COMPANY, OF CHICAGO, ILLINOIS, A CORPORATION OF ILLINOIS.

FILLED BAG SEWING MACHINE.

Application filed November 7, 1923. Serial No. 673,292.

The invention relates to new and useful improvements in filled bag sewing machines, and more particularly to a filled bag sewing machine wherein the mouth of the bag is 5 closed by a line of stitching.

An object of the invention is to provide a filled bag sewing machine of the above type wherein the stitching mechanism and the bag to be stitched are moved relative to each 10 other so as to form a straight line of stitching for closing the mouth of the bag, and wherein the moving means is returned to its initial position by gravity.

A further object of the invention is to 15 provide a machine of the above type wherein the sewing head is capable of being raised and lowered for bags of different heights, and wherein the stitching mechanism is connected to and disconnected from the operating mechanism by a treadle controlled means so arranged as to permit the adjustment of 20 the sewing head up or down without disturbing said treadle controlled mechanism, and wherein said treadle controlled mechanism includes an adjusting means for regulating the action of the treadle.

A further object of the invention is to 25 provide a machine of the above type wherein the driving mechanism for the sewing head includes a driving pulley mounted on the frame of the machine and a driving belt running over idlers disposed so that the sewing head may be raised and lowered without requiring any adjustments of the 30 idlers.

Another object of the invention is to provide a carrier for the bag being stitched, and tracks on which the carrier is adapted to move, which tracks are so mounted as to be 35 tilted after the bag is stitched and is removed from the carrier, so as to permit the carrier to return by gravity to its initial loading position.

Another object of the invention is to provide a machine of the above type wherein the tracks are tilted by means of springs and wherein the tracks may be lowered to horizontal position or even inclined downwardly, if desired, in the direction of feed 45 of the bag, by the treadle connection.

Still another object of the invention is to provide a machine of the above type wherein means is provided for raising and lower-

ing the tracks bodily, and wherein said treadle connections are so arranged as to 55 permit the raising and lowering of the tracks without disturbing in any way the means for depressing the tracks against the action of the lifting springs.

These and other objects will in part be 60 obvious and will in part be hereinafter more fully disclosed.

In the drawings which show by way of illustration one embodiment of the invention—

Figure 1 is an end view of a machine embodying our improvements;

Fig. 2 is a front view of the same;

Fig. 2^a is a detail showing the brake for holding the sewing head in adjusted positions;

Fig. 3 is a side view of the machine as viewed from the opposite side as shown in Fig. 1;

Fig. 4 is a transverse sectional view 75 through the track and showing the mechanism for elevating and depressing the track;

Fig. 5 is an end view of the track and the supports therefor, said view being taken from the free end of the track; and

Fig. 6 is a plan view of the track and the immediate supports therefor.

General structure.

Our improved filled bag sewing machine 85 includes a supporting base 1 which is preferably mounted so that it may be readily rolled about the mill, and means is provided for fixing the base in any desired shifted position. Rising from this base is a central 90 column 2 adjacent the upper end of which is mounted a sleeve 3 adapted to carry the sewing head 4. The sleeve is adjustable up and down on the column and the sewing head is adjustable toward and from the 95 column so as to vary the overhanging position of the sewing head. Also mounted on the column is another sleeve 5 which carries a support 6 on which is mounted tracks 7 for a carrier 8 for the bag being sewed. The 100 carrier is mounted so as to readily travel back and forth on the tracks. These tracks are pivoted and capable of being swung to a tilted position after the bag is removed therefrom so as to return the carrier to its 105 initial position. The tracks are depressed by

a treadle connection and may thus be brought down to a level position or a downwardly inclined position to facilitate the travel of the carrier during the stitching of the bag. The support for the tracks is also adjustable vertically, and the treadle connections are so arranged as not to be disturbed when the tracks are raised or lowered. The sewing head is controlled by a suitable clutch which is operated by treadle connections, and again these treadle connections are so arranged as not to be disturbed when the head is raised and lowered. The stitching mechanism is preferably driven from a driving pulley mounted on the base, and by means of a belt and idlers, which are so arranged as to permit the raising and lowering of the head without in any way requiring adjustment of the idlers. Means is also provided for adjusting the idlers so as to take up the slack in the driving belt.

Sewing head, and means for raising and lowering the same.

- 25 The sewing head 4 is of the usual type and includes a cylindrical support 9, an over-hanging arm 10, and a needle operating lever 11, which reciprocates a needle bar 12 carrying a needle, which moves back and forth in a horizontal line. Within the cylindrical work support 9 is a feeding mechanism, the feed dog being indicated at 13. These parts are of the usual construction and it is not thought necessary to go any further into a 30 detail description of the same. The sleeve 3 which carries the sewing head is provided with a forwardly projecting bracket 14. The sewing head is mounted on four pins 15 which are secured to the sewing head by means of screws 15^a. These pins slide in the bracket 14 and set screws 15^b are used for securing the pins in fixed position in the bracket. In order to aid in the adjusting of the head and setting it in proper position, 35 there is a threaded stud 16 carried by the head which passes through the bracket 14. Nuts 17 and 18 are threaded on this stud and operate to aid in the adjustment of the head and the securing of the head in adjusted position. By releasing these nuts and the set screws, the head may be moved in or out from the bracket. The sewing head is provided with a belt wheel 19. Mounted on the bracket 14 is a transmitter for transmitting 40 power to the sewing head. Said transmitter includes a belt wheel 20 mounted on a vertical shaft carried by suitable bearings in the bracket 14. On this shaft is a friction clutch 21 and a brake wheel 22. The clutch 45 is moved into engagement with its cooperating parts by means of a lever 23 which is pivoted at 24 and is provided with an arm 25 which shifts the friction clutch endwise of the vertical shaft and brings the parts into 50 driving connection. This happens when the

outer end of the lever is pulled downwardly. When the lever is released and raised by spring 25^a, a brake shoe 26 moves into engagement with the brake wheel on the transmitter and stops the stitching mechanism. 70 The friction clutch member is driven by a belt. A belt 27 connects the belt wheels 19 and 20.

On the supporting base of the machine there is a belt wheel mounted on a shaft 28, which shaft is driven by a belt wheel 29 and 75 a belt 30 leading from any suitable source of power. A belt 31 runs about the belt wheel on the shaft 28. One strand of this belt 31 runs over an idler 32 which is fixed to a bracket arm 33 carried by the column 80 2. After passing over the idler 32, this strand of the belt passes over an idler 34 carried by the bearing mounted on a depending arm 35 which is pivoted at 36 to the bracket 4 carrying the transmitter. Mounted 85 on this same depending arm is an idler 37. The other strand of the belt 31 runs over this idler 37, and the two strands of the belt then run horizontally and over the belt wheel on the shaft carrying the clutch member 21. It 90 will readily be seen that the sleeve carrying the sewing head can be moved up and down without in any way disturbing the driving connections. As the idler 34 moves upwardly, it will give up slack to the belt. At 95 the same time, the idler 37 is moving upwardly and will take up this slack so that the sewing head can be readily moved up and down, and as noted, the driving connections will not be disturbed. The depending arm 100 35 is adjustably connected to a rod 38 and this permits the idlers 34 and 37 to be adjusted toward and from the pulley on the transmitter and thus take up any slack in the driving belt.

105 The sleeve 3 carrying the sewing head slides freely up and down on the column 2. There is a vertical shaft 39 mounted in a bearing at the lower end of the column and also in a bearing at the upper end of the column. The upper portion of this shaft is smooth and passes through a small lug 40 carried by the sleeve 3. This lug slides freely on the shaft and the purpose of the shaft and lug is to prevent the sleeve from turning on the column. This shaft has other functions which will be described later. Mounted at the upper end of the column is a cross shaft 41, which carries a sprocket wheel 42 and also a large hand wheel 43. 110 A sprocket chain 44 is secured at one end to a hook 45 threaded into the bracket 14, which forms a part of the sleeve 3. The other end of this sprocket chain is connected to a counter-balancing weight 46 located 115 in the column. The sprocket chain has positive connection with the sprocket wheel, and when the sprocket wheel is turned through the hand wheel 43, then the chain will be moved so as to either raise or lower the 120 125 130

sewing head and the weight in the column counter-balances the weight of the head. There is preferably mounted on the cross shaft 41 a brake disk 47. This brake disk 5 is formed with hills and dales, and a spring 48 secured to the frame of the machine has its end rounded and is adapted to bear on this brake disk. The purpose of this spring 10 brake is to aid in holding the sewing head in any desired position, and at the same time, permits the head to be quickly and easily raised and lowered. Said hand wheel may be provided with a suitable handle 49 for turning the same.

15

Transmitter control.

Mounted on the base of the machine is a treadle 50. This treadle 50 extends from front to rear of the machine and is mounted 20 to rotate in suitable bearings. An arm 51 extends laterally from the treadle is adapted for the foot of the operator, so that the treadle shaft can be rotated through this foot treadle. Adjacent the rear end of the 25 shaft 50 is a laterally projecting arm 52. A flexible connection 53 extends from the end of the arm upwardly and over an idler 54 on the end of the transmitter lever 23. Said flexible connection extends thence over 30 another idler 55 which is mounted on the bracket 14. This flexible connection then extends on upwardly where it is connected to a turn buckle 56 and the turn buckle is in turn connected to a bracket 56' at the upper 35 end of the machine. It will readily be seen that when the treadle is depressed, the idler 54 will be moved downwardly, thus swinging the transmitter lever, and when released, the spring controlling the transmitter will 40 of course, raise this idler. When the sleeve carrying the sewing head is moved up and down, both idlers 54 and 55 will move therewith, and as one gives up slack in this flexible connection 53, the other will take it up, 45 so that the sleeve is capable of up and down movements without disturbing in any way the treadle connection to the transmitter. When it is desired to vary the action of the 50 treadle connection on the transmitter, then the turn buckle 56 is either taken up or let out, and this shortens the flexible connection 53 and thus varies the released position of the transmitter lever.

55

Track supporting mechanism.

As has already been referred to, there is a carrier 8 for the filled bag which moves back and forth on tracks 7. These tracks are carried by a frame structure which includes a sleeve 5 mounted on the column, the 60 arms 57, 57 formed integral with the sleeve and projecting therefrom. These arms project downwardly and thence forwardly to the front of the machine. The sleeve 5 is 65 provided with a threaded lug 58 which en-

gages a threaded portion 59 of the vertical shaft 39. This vertical shaft is rotated by means of a hand wheel 60 mounted on a shaft 60' which is carried by a suitable bracket mounted on the column 2. The 70 shaft carries a bevel gear 61 which meshes with a bevel gear 62 secured to this vertical shaft 39. The rotating of the hand wheel 60 will rotate the vertical shaft, and this will raise and lower the sleeve carrying the 75 supporting structure for the tracks. The tracks comprise two parallel connected U-shaped members 63. These members are connected by suitable rods 83, which rods are provided with rollers 65 on which the 80 carrier is supported and travels. We have referred to these members as tracks for the carrier, using this term in the broad sense, and meaning a means on which the carrier travels back and forth, and not necessarily 85 members on which wheels travel, although it is obvious that a carrier may be mounted on wheels if so desired. The carrier is prevented from lateral movement on the tracks by means of rollers 66 carried by vertical 90 stud members on the carrier, and adapted to engage guide plates 67, 67', respectively, at opposite sides of the tracks. This carrier as shown consists of upper and lower members, one above and the other below the guide 95 plates. The particular construction of the carrier and the tracks, as a matter of fact, form no part of the present invention, but are shown, described and claimed in our co-pending application, Serial No. 597,615, filed 100 October 28, 1922.

From the above it will be noted that the carrier really moves back and forth on the rollers 65, and these rollers constitute the supporting means for the carrier. The carrier has an upturned part 66' at its rear end. The bag is placed on the carrier and then the carrier moved forward as the sewing proceeds, and thus it is that the bag is conveyed past the needle during the stitching 110 of the bag.

Mechanism for tilting tracks.

The tracks are pivoted at 67' to one of the supporting arms 57 and extend across the 115 machine above the other supporting arm 57. Said right-hand supporting arm 57 as viewed in Fig. 2, is formed with an angle plate 68 which carries the pivot for the tracks. The other, or left-hand supporting arm 57 is provided with an angle plate 69. There is a standard 70 at each side of the track threaded into this angle plate 69. These standards extend through perforated lugs 71 carried by the U-shaped members 63. There is a coiled 120 spring 72 surrounding each standard. This spring at the upper end bears against the lug 71, and at its lower end bears against a washer 72' carried by a nut 73 which may be adjusted up and down on the standard 70, 125 130

It will thus be seen that the left-hand end of the track may be depressed and at such time, the springs 70 will be compressed while the standards 70 will pass upwardly through the 5 openings in the lug 71. When the tracks are free from weight, the carrier will be positioned as shown in Fig. 2, with the left-hand end raised through the springs referred to.

We have provided means for lowering this 10 end of the track which is controlled from the treadle 51. On the shaft 50 adjacent the treadle is a projecting arm 74. A flexible member 75 connected to the arm 74 runs over an idler 76 carried by a cross bar 77 which 15 is attached to the U-shaped members forming the track for the carrier. This flexible member thence runs over an idler 78 carried by one of the supporting arms 57. Said flexible member runs up through the arm or support 20 57 freely and it is attached to a bracket arm 79 carried by a fixed collar on the column 2. It will readily be seen that when the treadle is depressed, the idler 76 will be lowered and this will draw the left-hand end of the tracks 25 downwardly. The tracks may be lowered until the adjustable stops 80 engage the U-shaped members 63. These adjustable stops are carried by angle brackets 81 mounted on one of the supports 57, and the stops are held 30 in adjusted position by means of lock nuts 82. These stops can be readily raised or lowered, and this will determine the lower position of the tracks. The stops may be set so that when the tracks are lowered, they will 35 be level, or they may be set below this position, so that the left-hand end of the tracks when lowered is such that the tracks incline downwardly from right to left or in the direction of travel of the carrier during the 40 sewing. This is for the purpose of aiding in the free movement of the carrier when loaded with a heavy bag and during sewing, so that the sewing machine feed will, without any difficulty, move the bag while it is being 45 stitched. The sewing machine feed can also move the bag when the carrier moves in a horizontal plane as the carrier is mounted to move on rollers and is very light. As soon as the bag has been completely stitched and 50 the operator lifts the same from the tracks, he releases his foot from the treadle, and the springs raise the left-hand end of the tracks, so that the carrier will move back to its initial position for loading. When the car- 55 rier is in initial position for loading, the central part thereof is preferably substantially over the pivotal point 67 for the tracks, and this enables the bag to be tamped and the contents properly settled therein 60 before feeding along to the stitching mechanism.

While the transmitter lever and the tracks are both arranged by the same treadle, the flexible connections can be so proportioned 65 that the tracks will be lowered first before

the transmitter is operated to start the stitching mechanism.

Stops for the carrier.

The U-shaped members 63 forming the 70 tracks, are connected at their outer ends by rods 83. These rods project rearwardly beyond the U-shaped members 63 at the rear of the machine and carry a rod 84 which extends the full length of the tracks. This rod 75 84 is provided with an adjustable bracket 85 in which is mounted a buffer 86. It also carries a bracket 87 in which is mounted a buffer 88. There is a suitable lug 89 on the carrier which is adapted to engage the buffer 80 88 when the carrier moves forward to limit the travel of the carrier and prevent it from running off the tracks and the same lug is adapted to engage the buffer 86 when the carrier is moved to the right, and stops the 85 carrier at its initial loading position.

These stops are made adjustable for the reason that various sized bags vary in width of mouth, and it is desired to have the carrier only travel a sufficient distance to convey the bag to the stitching mechanism and then return. This saves time and considerable wear and tear on the machine. 90

Operation.

95

It is thought that the operation of our device will be clear from the description given above in detail. The bags to be closed are filled and are placed by the operator on the carrier which at the time, is at the right-hand end of its travel, as viewed from the front of the machine. The mouth of the bag is then raised so as to be directed into the feed of the sewing machine, and the operator by placing his foot on the treadle, depresses the tracks preparatory to the forward movement of the carrier, and this shifts the transmitter to start the stitching mechanism. The bag is fed through the machine by the feed of the sewing machine and the carrier travels along therewith. After the bag has passed through and the stitching is completed, the operator releases the treadle which stops the stitching mechanism, and when the bag is lifted from the carrier, the tracks will be raised by the spring, and the carrier will automatically return to its initial loading position by gravity. 110 115

If a different sized bag is to be stitched and the variation is only slight compared with the one previously stitched, then the sewing head may be quickly raised or lowered by the hand wheel 43 and this may be done without in any way disturbing either the driving connections for the sewing head 120 or the treadle connection for the transmitter. If a greater range of adjustment is desired, this can be done by turning the hand wheel 60 which will turn the vertical shaft 39 and thus raise and lower the support for the 125 130

tracks. This may be done also without in any way disturbing the treadle connections for tilting the tracks. In fact, both the sewing head and the tracks may be moved 5 toward each other or away from each other if desired.

From the above it will be noted that we have provided a machine which is very simple in construction, capable of very wide 10 adjustments, and which requires a minimum amount of power for operating; also a machine wherein the bags may be quickly stitched and the machine again brought into position for the next bag. It is clearly a 15 one-man machine wherein all the parts to be actuated by the operator, are readily accessible to him.

It is obvious that minor changes in the 20 details of construction and the arrangement of the parts may be made without departing from the spirit of the invention as set forth in the appended claims.

Having thus described the invention, what 25 we claim as new and desire to secure by Letters-Patent, is—

1. A filled bag sewing machine including a frame, a support carried thereby, tracks mounted on said support and normally disposed in substantially horizontal position, a 30 sewing head on the frame overhanging the tracks, a carrier adapted to move freely back and forth on said tracks, and means for inclining said tracks downwardly toward the initial loading position of the carrier after 35 the stitched bag is removed from the carrier whereby said carrier may be returned by gravity to its initial loading position.

2. A filled bag sewing machine including a frame, a support carried thereby, tracks mounted on said support and normally disposed in substantially horizontal position, a 45 sewing head on said frame and overhanging said tracks and having a horizontally disposed needle, a carrier for the filled bag adapted to move freely along said tracks, means for automatically inclining said 50 tracks downwardly toward the initial loading position of the carrier after the stitched bag is removed therefrom, whereby said carrier is returned by gravity to its initial loading position.

3. A filled bag sewing machine including a frame, a support carried thereby, a sewing head carried by said frame, and overhanging 55 said support, a carrier for the filled bag adapted to move along said support during the stitching of the bag, said support being inclined downwardly toward the initial loading position of the carrier during the return 60 of the same whereby the carrier is returned by gravity after the stitched filled bag is removed therefrom, and an adjustable stop mounted on the support for stopping the carrier at initial loading position.

65 4. A filled bag sewing machine including a

frame, a support carried thereby, a sewing head carried by said frame, and overhanging said support, a carrier for the filled bag adapted to move along said support during the stitching of the bag, said support being 70 inclined downwardly toward the initial loading position of the carrier during the return of the same whereby the carrier is returned by gravity after the stitched filled bag is removed therefrom, means for actuating 75 said sewing head including devices whereby the sewing head may be connected to or disconnected from its actuating means, a lever for controlling said connecting means, a foot treadle, means for raising and lowering the 80 sewing head relative to the support, and devices controlled by the foot treadle for operating said lever, said devices being arranged so as to permit the sewing head to be raised and lowered without disturbing the treadle 85 operated connection.

5. A filled bag sewing machine including in combination, a supporting base, a column rising therefrom, a support mounted on said column, a sewing head mounted on said column and overhanging said support, a carrier for the filled bag adapted to move along said support during the stitching of the bag, said support being inclined downwardly toward the initial loading position 90 of the carrier during the return of the same whereby the carrier is returned by gravity after the stitched filled bag is removed therefrom, said column having a sleeve mounted thereon for carrying the sewing head, and means for raising and lowering said sleeve for positioning the sewing head at different heights relative to the support for the filled bag, and means whereby said sewing head may be moved toward and from the column for positioning the sewing head centrally over the bag.

6. A filled bag sewing machine including in combination, a supporting base, a column rising therefrom, a support mounted on said column, a sewing head mounted on said column and overhanging said support, a carrier for the filled bag adapted to move along said support during the stitching of the bag, said support being inclined downwardly toward the initial loading position 110 of the carrier during the return of the same whereby the carrier is returned by gravity after the stitched filled bag is removed therefrom, said column having a sleeve mounted thereon for carrying the sewing head, and means for raising and lowering said sleeve for positioning the sewing head at different heights relative to the support for the filled bag, means whereby said sewing head may be moved toward and from the column for positioning the sewing head centrally over the bag, and means for raising and lowering said support.

7. A filled bag sewing machine including 120

in combination, a supporting base, wheels on which said base is mounted whereby it may be readily moved from place to place, means for securing said base in set position, 5 a column carried by the base and extending upwardly therefrom, a sleeve mounted for adjustment on said column, a support carried by the sleeve, a second sleeve mounted on said column, a sewing head carried thereon 10 by and overhanging said support, a carrier for the filled bag adapted to move along said support during the stitching of the bag, said carrier being inclined downwardly toward the initial loading position of the same 15 whereby the carrier will be returned by gravity after the stitched filled bag is removed therefrom.

8. A filled bag sewing machine including in combination, a frame, a support carried 20 by said frame, tracks normally disposed in substantially a horizontal position and connected to said support whereby the same may be moved to an inclined position, a sewing head carried by the frame and overhanging said tracks, a carrier for the filled bag adapted to move along the tracks during the stitching of the bag, and means 25 operating to move said tracks so as to tilt the same for returning the carrier after the 30 stitched bag has been removed therefrom.

9. A filled bag sewing machine including in combination, a frame, a support carried by said frame, tracks normally disposed in substantially a horizontal position and connected to said support whereby the same may be moved to an inclined position, a sewing head carried by the frame and overhanging said tracks, a carrier for the filled bag adapted to move along the tracks during the 35 stitching of the bag, means operating to move said tracks so as to tilt the same for returning the carrier after the stitched bag has been removed therefrom, and means for raising and lowering the support for the 40 tracks.

10. A filled bag sewing machine including in combination, a frame, a support carried by said frame, tracks connected to said support whereby the same may be moved to 50 an inclined position, a sewing head carried by the frame and overhanging said tracks, a carrier for the filled bag adapted to move along the tracks during the stitching of the bag, means under the control of the operator for moving said tracks so as to tilt the same for returning the carrier after the stitched bag has been removed therefrom, means whereby said sewing head may be raised and lowered relative to the support, 55 and means whereby said support may be raised and lowered relative to the sewing head.

11. A filled bag sewing machine including in combination, a frame, a support carried 60 by said frame, tracks connected to said sup-

port whereby the same may be moved to an inclined position, a sewing head carried by the frame and overhanging said tracks, a carrier for the filled bag adapted to move along the tracks during the stitching of the bag, 70 means under the control of the operator for moving said tracks so as to tilt the same for returning the carrier after the stitched bag has been removed therefrom, means whereby said sewing head may be raised and lowered 75 relative to the support, and means whereby the sewing head may be moved toward and from the frame whereby the same may be centrally positioned over the carrier.

12. A filled bag sewing machine including 80 in combination, a supporting base, a column rising therefrom, a sleeve mounted on said column for vertical adjustment, a support carried by said sleeve, tracks mounted on the support and adapted to be tilted, a carrier for 85 the filled bag adapted to move along said support during the stitching of the bag, said tracks being inclined downwardly toward the initial loading position of the carrier so as to return the carrier to its loading position when 90 the filled stitched bag is removed therefrom, a sewing head mounted on said column and overhanging said carrier, and means for raising and lowering the sewing head.

13. A filled bag sewing machine including 95 in combination, a supporting base, a column rising therefrom, a sleeve mounted on said column for vertical adjustment, a support carried by said sleeve, tracks mounted on the support and adapted to be tilted, a carrier 100 for the filled bag adapted to move along said support during the stitching of the bag, said tracks being inclined downwardly toward the initial loading position of the carrier so as to return the carrier to its loading position 105 when the filled stitched bag is removed therefrom, a sewing head mounted on said column and overhanging said carrier, means for raising and lowering the sewing head, means for normally holding said tracks in raised 110 tilted position, and treadle controlled means for lowering the tracks to substantially horizontal position.

14. A filled bag sewing machine including 115 in combination, a supporting base, a column rising therefrom, a sleeve mounted on the column, means for raising and lowering the sleeve on said column, a support carried by said sleeve, tracks pivotally mounted upon said support, a carrier for the filled bag 120 adapted to move along said tracks during the stitching of the bag, said pivot for the tracks being located near the initial loading position for the carrier, springs located at the other end of the tracks for raising the same to inclined position, a sewing head mounted on the column and overhanging said carrier, a treadle for depressing the tracks, and adjustable stops for limiting the downward movement of the swinging end of the tracks. 125 130

15. A filled bag sewing machine including in combination, a supporting base, a column rising therefrom, a sleeve mounted on the column, means for raising and lowering the sleeve on said column, a support carried by said sleeve, tracks pivotally mounted upon said support, a carrier for the filled bag, adapted to move along said tracks during the stitching of the bag, said pivot for the tracks being located near the initial loading position for the carrier, springs located at the other end of the tracks for raising the same to inclined position, a sewing head mounted on the column and overhanging said carrier, a treadle for depressing the tracks, adjustable stops for limiting the downward movement of the swinging end of the tracks, means for raising and lowering the support for the tracks, said treadle controlled means for lowering the tracks including devices which permit the support to be adjusted vertically without requiring any adjustment of the treadle controlled devices. 70
16. A filled bag sewing machine including in combination, a frame, a support carried by the frame, means whereby said support may be raised and lowered, tracks pivotally carried by said support, springs for raising said tracks to an inclined position, a treadle carried by the frame, a flexible member connected to the frame and to the treadle, and devices over which said flexible member runs arranged so that the depression of the treadle will lower the tracks and so that said support may be raised and lowered without interfering with said treadle connection for depressing the tracks. 80
17. A filled bag sewing machine including in combination, a supporting base, a column carried thereby, a sleeve carried by the column, means for raising and lowering said sleeve on the column, laterally projecting arms carried by the sleeve, a support mounted on said arms, tracks pivotally mounted upon said support, vertically projecting members carried by the support, lugs carried by the tracks and engaging said vertically projecting members and adapted to move up and down on said members, springs surrounding said vertical members and bearing against the lugs for normally raising the tracks, and means whereby said tracks may be depressed. 90
18. A filled bag sewing machine including in combination, a supporting base, a column carried thereby, a sleeve carried by the column, means for raising and lowering said sleeve on the column, laterally projecting arms carried by the sleeve, a support mounted on said arms, tracks pivotally mounted upon said support, vertically projecting members carried by the support, lugs carried by the tracks and engaging said vertically projecting members and adapted to move up and down on said members, springs surrounding said vertical members and bearing 100
19. A filled bag sewing machine including in combination, a supporting base, a column carried thereby, a sleeve carried by the column, means for raising and lowering said sleeve on the column, laterally projecting arms carried by the sleeve, a support mounted on said arms, tracks pivotally mounted upon said support, vertically projecting members carried by the support, lugs carried by the tracks and engaging said vertically projecting members and adapted to move up and down on said members, springs surrounding said vertical members and bearing 110
20. A filled bag sewing machine including in combination, a supporting base, a frame carried thereby, a support mounted on said frame, tracks carried by the support, a carrier for the filled bag adapted to move along said tracks during the stitching of the bag, said tracks being substantially horizontal during the forward movement of the carrier and means for tilting said tracks so as to cause the carrier to return by gravity to initial loading position when the bag is removed therefrom. 120
21. A filled bag sewing machine including in combination, a supporting base, a frame carried thereby, a support mounted on said frame, tracks carried by the support, a carrier for the filled bag adapted to move along said tracks during the stitching of the bag, said tracks being substantially horizontal during the forward movement of the carrier 130

and being tilted so as to cause the carrier to return to loading position by gravity when the bag is removed therefrom, and an adjustable stop for limiting the return movement of the carrier and holding the same at loading position.

22. A filled bag sewing machine including in combination, a supporting base, a frame carried thereby, a support mounted on said frame, tracks carried by the support, a carrier for the filled bag adapted to move along said tracks during the stitching of the bag, said tracks being substantially horizontal during the forward movement of the carrier and being tilted so as to cause the carrier to return to loading position by gravity when the bag is removed therefrom, an adjustable stop for limiting the return movement of the carrier and holding the same at loading position, and an adjustable stop for limiting the forward travel of the carrier while the bag is being stitched.

23. A filled bag sewing machine including in combination, a frame, a support vertically adjustable on said frame, tracks mounted on said support, said tracks being pivoted, a carrier for the filled bag adapted to move along said tracks during the stitching of the bag, springs for normally holding the tracks raised so as to return the carrier by gravity when the filled bag is removed therefrom, a treadle, means operated by the treadle for depressing the tracks including a flexible member, and idlers so arranged as to permit the tracks to be vertically adjusted without disturbing said treadle connections, a sewing head adapted to move vertically on said frame, means for controlling the operation of the sewing head including a lever, a flexible connection and idlers whereby said lever can be actuated from said treadle, said idlers and flexible connection being arranged so as to permit the sewing head to be vertically adjusted without disturbing said connections, said treadle connections for the tracks and said treadle connections for the head being so arranged that the tracks may be depressed to substantially horizontal position prior to the starting of the stitching mechanism.

24. A filled bag sewing machine including in combination a supporting base, a column carried thereby, a bracket mounted on said column, a sewing head carried by the bracket, a weight located in the column, a shaft mounted at the upper end of said column and carrying a sprocket wheel, a sprocket chain running over said sprocket wheel and connected at one end to said weight and at its other end to said bracket, a hand wheel for rotating said shaft whereby the bracket and sewing head carried thereby may be raised and lowered, and means yieldable to a force applied to the hand

wheel for holding said bracket in various set 65 positions.

25. A filled bag sewing machine including in combination, a supporting base, a column carried thereby, a sleeve mounted on said column, a sewing head carried by the sleeve, a weight located in the column, a shaft mounted at the upper end of said column and carrying a sprocket wheel, a sprocket chain connected at one end to said weight, and at its other end to said sleeve, a hand wheel for rotating said shaft whereby the sleeve and sewing head carried thereby may be raised and lowered, a brake disk carried by said shaft and having depressions therein, and a spring carried by the column and adapted to bear on the brake disk for holding the sleeve and sewing head in various adjusted positions.

26. A filled bag sewing machine including in combination, a supporting base, a column carried thereby, sleeve mounted on said column, a sewing head carried by the sleeve, a weight located in the column, a shaft mounted at the upper end of said column and carrying a sprocket wheel, a sprocket chain connected at one end to said weight and at its other end to said sleeve, a hand wheel for rotating said shaft whereby the sleeve and sewing head carried thereby may be raised and lowered, an actuating shaft 85 for the sewing head mounted on the base, idlers mounted on the sleeve and on the column for the driving belt, said idlers being arranged so that the sewing head can be raised and lowered without disturbing 90 the driving connection.

27. A filled bag sewing machine including in combination, a supporting base, a column carried thereby, a sleeve mounted on said column, a sewing head carried by the sleeve, a weight located in the column, a shaft mounted at the upper end of said column and carrying a sprocket wheel, a sprocket chain connected at one end to said weight and at its other end to said sleeve, a hand wheel for rotating said shaft whereby the sleeve and sewing head carried thereby may be raised and lowered, means for controlling the operation of the sewing head including a lever movable up and down with the sewing head, a treadle, an idler carried by the lever, an idler mounted on the sleeve and movable up and down therewith and located below the idler on the lever, and a flexible member connected to the treadle and extending over said idlers and connected to the column.

28. A filled bag sewing machine including in combination, a supporting base, a column carried thereby, a sleeve mounted on said column, a sewing head carried by the sleeve, a weight located in the column, a shaft mounted at the upper end of said column

and carrying a sprocket wheel, a sprocket chain connected at one end to said weight and at its other end to said sleeve, a hand wheel for rotating said shaft whereby the 5 sleeve and sewing head carried thereby may be raised and lowered, means for controlling the operation of the sewing head, including a lever movable up and down with the sewing head, a treadle, an idler carried by 10 the lever, an idler mounted on the sleeve and movable up and down therewith and located below the idler on the lever, and a flexible member connected to the treadle and extending over said idlers and connected to 15 the column, said connection between the flexible member and the column including a turn buckle capable of adjustment for varying the initial position of the lever.

29. A filled bag sewing machine including 20 in combination, a supporting base, a frame carried thereby, a support carried by the frame, means for raising and lowering said support on the frame, a sewing head carried by the support, a transmitter mounted on 25 said support, a lever for controlling said transmitter, a treadle mounted on the base, an idler carried by the lever, an idler mounted on the support beneath the lever, a flexible member connected to the treadle and 30 extending over the idler on the lever, thence over the idler on the support and connected to the frame whereby when said treadle is depressed, the lever will be depressed and whereby said support may be raised and 35 lowered without requiring adjustment of the treadle connections.

30. A filled bag sewing machine including 40 in combination, a supporting base, a frame carried thereby, a support carried by the frame, means for raising and lowering said support on the frame, a sewing head carried by the support, a transmitter mounted on 45 said support, a lever for controlling said transmitter, a treadle mounted on the base, an idler carried by the lever, an idler mounted on the support beneath the lever, a flexible member connected to the treadle and extending over the idler on the lever, thence over the idler on the support and connected to 50 the frame whereby when said treadle is depressed, the lever will be depressed and whereby said support may be raised and lowered without requiring adjustment of the treadle connections, said connection between the flexible member and the frame including a turn buckle capable of adjustment for varying the position of the transmitter lever.

31. The combination of a frame, a support carried by the frame, means whereby the support may be raised and lowered, an operating treadle carried by the frame, a shiftable device carried by said support, a flexible member, and idlers for connecting 65 said treadle to said shiftable device whereby

said device may be shifted and whereby said support may move up and down and the flexible member run freely over the idlers without shifting the same.

32. The combination of a frame, a support carried by the frame, means whereby said support may be raised and lowered, a shiftable device carried by said support, a treadle, an idler mounted on said shiftable device, an idler mounted on the support beneath the idler on the shiftable device, a flexible member connected to said treadle and running over, first the idler on the shiftable device, thence over the idler on the support and attached to the frame at a point above said shiftable device whereby the depressing of the treadle will shift said device, and whereby said support may be raised and lowered without shifting said device. 70 75 80

33. The combination of a frame, a support carried by the frame, means whereby said support may be raised and lowered, a shiftable device carried by said support, a treadle, an idler mounted on said shiftable device, an idler mounted on the support beneath the idler on the shiftable device, a flexible member connected to said treadle and running over, first the idler on the shiftable device, thence over the idler on the support and attached to the frame at a point above said shiftable device whereby the depressing of the treadle will shift said device, and whereby said support may be raised and lowered without shifting said device, said connection between the flexible member and the support at the upper end thereof including means whereby the flexible member may be shortened so as to vary the position of the shiftable device. 90 95 100 105

34. The combination of a frame, a support carried by said frame, tracks pivotally connected to the support whereby the same may be moved to an inclined position, an operating head carried by the frame and overhanging said tracks, a carrier for the article to be operated upon adapted to move along the tracks, means under the control of the operator for moving said tracks so as to tilt the same for returning the carrier after said article has been removed therefrom. 110 115

35. The combination of a frame, a support carried by said frame, tracks pivotally connected to the support whereby the same may be moved to an inclined position, an operating head carried by the frame and overhanging said tracks, a carrier for the article to be operated upon adapted to move along the tracks, means under the control of the operator for moving said tracks so as to tilt the same for returning the carrier after said article has been removed therefrom, said controlling means including devices which permit the support to be ad- 120 125 130

justed without disturbing said operating devices.

36. The combination of a frame, a support carried thereby and capable of vertical 5 adjustments, tracks pivoted to the support whereby the same may be moved to an inclined position, an operating head carried by the frame and overhanging the tracks, a carrier for the article to be operated upon 10 adapted to move along the tracks, a treadle mounted on the frame beneath the tracks, a flexible connection, and idlers for connecting said treadle to the tracks for depressing said tracks, so as to permit the ready movement 15 of the carrier toward the operating head, and springs for raising the tracks when released by the treadle, said idlers being so disposed as to permit the support to be raised and lowered without requiring 20 any adjustment of the treadle operated means.

37. A filled bag sewing machine including in combination a supporting base, a frame carried thereby, a support carried by 25 the frame, means for raising and lowering said support on the frame, a sewing head carried by the support, means for actuating the sewing head including a clutch mounted on the support and movable up 30 and down therewith, a lever mounted on the support for controlling the clutch, a treadle mounted on the base, an idler carried by the

lever, an idler mounted on the support, a flexible member connected to the treadle and extending over the idler on the lever, thence over the idler on the support, and connected to the frame whereby when said treadle is depressed the lever will be depressed, and whereby said support may be raised and lowered without requiring adjustment of the treadle connections. 35 40

38. A filled bag sewing machine including in combination a supporting base, a frame carried thereby, a support carried by the frame, means for raising and lowering 45 said support on the frame, a sewing head carried by the support, means for actuating the sewing head including a clutch mounted on the support and movable up and down therewith, and treadle actuated means for 50 controlling the clutch including a flexible member connected at one end to said treadle and at its other end to said frame, said flexible member being connected to said clutch so that when said treadle is depressed, the 55 clutch will be operated, said connection permitting said support and sewing head to be raised and lowered without requiring adjustment of the treadle actuated means.

In testimony whereof, we affix our signatures. 60

CHARLES S. THOMPSON.
